B. H. MARSHALL

WREATH

Filed Dec. 21, 1923

Fig. 4.

Fig. 5.

UNITED STATES PATENT OFFICE.

BURNS HENRY MARSHALL, OF DETROIT, MICHIGAN.

WREATH.

Application filed December 21, 1923. Serial No. 682,030.

To all whom it may concern:

Be it known that I, BURNS H. MARSHALL, a citizen of the United States, residing at Detroit, in the county of Wayne, State of Michigan, have invented certain new and useful Improvements in Wreaths, of which the following is a specification.

My invention relates to improvements in decorative wreaths which in general are of a floral nature, and it consists in the combinations, constructions and arrangements of parts herein described and claimed.

An object of the invention is to provide a wreath of the character described which is formed of sections made of cardboard, light gage metal, or like material, each of the sections being fashioned in the similitude of foliage and the several sections being connected together in such manner that the wreath composed thereof has a natural and highly ornamental appearance.

A further object of the invention is to provide a wreath of the character described which is adapted to be produced at a relatively low cost and which is not likely to get out of shape readily.

Other objects and advantages will be apparent from the following description, considered in conjunction with the accompanying drawings, in which:

Figure 1 is a plan view of an incomplete wreath showing the manner of assembling certain of the elements thereof,

Figure 2 is a fragmentary perspective view showing the relation of a foliage section and a spacing section of the wreath to each other and to a binding wire,

Figure 3 is a plan view of a ring-shaped binding wire which may be comprised in the wreath,

Figure 4 is a plan view of one of the spacers opened out, and

Figure 5 is a plan view of one of the foliage sections in opened out or unfolded position.

A wreath embodying the invention in the form now preferred by me comprises alternating foliage and spacer sections 1 and 2, respectively, bound together and carried by a binding ring 3. Each of the foliage sections 1 comprises a palmated body formed of a thin sheet of cardboard, thin gage metal, or other suitable flexible and resilient material.

The palmated body of which each of the sections 1 consists is clearly shown in Figure

5, and the material of which it is composed may be colored, embossed, or have any desirable printing or indicia, or design produced thereon. The palmated body has finger-like radial prolongations 4 which have the edges thereof serrated or curved as shown in imitation of the marginal line of a leaf of any particular tree or flower, as for instance, the leaf of holly. The palmated body may be bent substantially into conical shape and is held in such shape by the engagement of a tab or lug portion 5 thereof at one lateral edge of the body with a slot 6 which is located adjacent to the opposite lateral edge of the body, the slotted portion of the body being overlapped by the tab-carrying portion of the body.

The sections 1 are strung on the binding wire 3 and each two adjacent sections 1 are spaced apart by one of the spacers 2. Each of the spacers 2 comprises a flat body consisting of two elongated similar portions 7 which have angular end portions indicated at 7^a, each of such angular end portions being united along one lateral edge to the other angular end portion, thus producing a fold line, indicated at 8, so that one of the portions 7 may be folded to overlie the other portion 7 and will then be co-extensive in area with the latter. The portions 7 of each spacer are reduced in width adjacent to their free ends as indicated at 9 to provide tongues 10 and the superposed tongues of each folded spacer may be inserted through the slot 6 of the preceding section 1 on the binding wire. The succeeding section 1 on the binding wire receives the folded angular end portions of the spacer and is held by the latter in spaced relation to the preceding foliage section 1.

The binding wire 3 may be a single length of spring wire bent into circular shape and having lapped end portions.

From the foregoing description of the various parts of the device the operation thereof may be readily understood. When the foliage sections and the spacer sections are arranged in alternating relation circumferentially of the binding wire 3, the spacers will be practically completely encompassed and concealed by the foliage sections and the portion of each foliage section which carries the leaf-resembling prolongations 4 likewise will be practically completely concealed by the leaf-resembling por-

tions of the adjacent foliage section so that the effect of a continuous series of leaves encircling the binding ring will be produced.

Obviously, the invention is susceptible of embodiment in forms other than that illustrated in the accompanying drawings and I, therefore, consider as my own all modifications and adaptations thereof which fairly fall within the scope of the appended claims.

10 I claim:

1. A wreath comprising a plurality of alternating foliage sections made of a flexible material and spacers, and means holding said foliage sections and spacers in ring formation.

15 2. A wreath comprising a plurality of sections, each formed of a flexible material bent to provide a substantially conical-shaped portion having leaf-resembling prolongations at one end thereof, a binding wire extending through said sections, and a spacer between each two adjacent sections.

20 3. A wreath comprising a plurality of sections, each formed of a flexible material bent to provide a substantially conical-shaped portion having leaf-resembling prolongations at one end thereof, a binding wire extending through said sections, a spacer between each two adjacent sections, said 25 spacer conforming in color to said sections and being made of a material similar to the material of which said sections are composed.

30 35 4. A wreath comprising a plurality of sections, each formed of a flexible material bent to provide a substantially conical-shaped portion having leaf-resembling prolongations at one end thereof, a binding wire extending through said sections, a spacer between each two adjacent sections, each 40 spacer being attached to one of said sections and being partially received within the coni-

cal-shaped portion of the succeeding section.

5. In a wreath, a section comprising a palmated flat body made of a flexible material, 45 the marginal line of each finger-like portion of the body conforming substantially to the marginal line of the leaf of a particular flower or tree, the palmated portion of said body having cooperative co-engaging means 50 whereby said body will be held substantially in conical shape, and means whereby a plurality of said sections may be connected together in series to form a wreath.

6. In a wreath, a section comprising a palmated flat body made of a flexible material, the marginal line of each finger-like portion of the body conforming substantially to the marginal line of the leaf of a particular flower or tree, the palmated portion of said body having co-operative co-engaging means 55 whereby said body will be held substantially in conical shape, means whereby a plurality of said sections may be connected together in series to form a wreath, and a spacer between each two adjacent sections of said wreath.

7. In a wreath, a section comprising a palmated flat body made of a flexible material, the marginal line of each finger-like portion 70 of the body conforming substantially to the marginal line of the leaf of a particular flower or tree, the palmated portion of said body having co-operative co-engaging means whereby said body will be held substantially 75 in conical shape, means whereby a plurality of said sections may be connected together in series to form a wreath, and a spacer between each two adjacent sections of said wreath, said spacer being detachably secured to the preceding section and engaging with the succeeding section to hold the sections in spaced apart relation.

BURNS HENRY MARSHALL.
